United States Patent Office

Des. 196,300
Patented Sept. 17, 1963

196,300

PICTURE HOOK OR SIMILAR ARTICLE

Otto Isensee, Jr., Glenview, Ill., assignor to Bull Dog Lock Company, Chicago, Ill., a corporation of Illinois

Filed Apr. 28, 1960, Ser. No. 60,355

Term of patent 14 years

(Cl. D17—12)

FIG. 2

The dotted line showing of a nail is for illustrative purposes only.

I claim:

The ornamental design for a picture hook or similar article, as shown and described.
